D. F. FESLER

LUBRICATING MEANS

Filed Aug. 8, 1921

Inventor
Douglas F. Fesler
Williams, Bradley,
See, & McClint. Atlys.

UNITED STATES PATENT OFFICE.

DOUGLAS F. FESLER, OF EVANSTON, ILLINOIS, ASSIGNOR TO THE BASSICK MANUFACTURING COMPANY, OF CHICAGO, ILLINOIS, A CORPORATION OF DELAWARE.

LUBRICATING MEANS.

Application filed August 8, 1921. Serial No. 490,491.

To all whom it may concern:

Be it known that I, DOUGLAS F. FESLER, a citizen of the United States, and resident of Evanston, in the county of Cook and State of Illinois, have invented a certain new and useful Improvement in Lubricating Means, of which the following is a full, clear, concise, and exact description, reference being had to the accompanying drawings, forming a part of this specification.

My invention relates to improvements in lubricating means, and is particularly concerned with the provision of novel means for expediting and facilitating the filling of lubricant compressors, grease cups, etc.

The objects of my invention are—

First: To provide a novel type of container or cartridge for holding a charge of lubricant to be inserted in a lubricant compressor or grease cup, the said cartridge comprising means for displacing the contents therefrom;

Second: To provide a container of the character described which can be easily and quickly connected with the open end of a lubricant compressor or grease cup so that the contents of the container can be transferred to the compressor or grease cup without loss of any of the contents, and without soiling the hands of the operator;

Third: To provide a container of the character described which is simple in construction, and economical to manufacture, and

Fourth: To provide a novel lubricant package which can be transported without danger of loss of the contents thereof, and which can be manipulated to easily and quickly fill the barrel of the lubricant compressor or grease cups.

Other objects will appear as this description progresses, reference being had to the accompanying drawings in which—

Figure 1 is a side elevation of my improved grease cartridge.

Figure 2 is a central longitudinal section;

Figure 3 is an end view showing one of the end closures removed, and,

Figure 4 is a view partially in longitudinal section, showing the method of using my improved cartridge for filling the barrel of a grease gun.

Throughout the several views, similar reference characters will be used for referring to similar parts.

My improved cartridge or lubricating means comprises a cylindrical container 5 which is preferably formed of two concentric tubes 6 and 7 of fibre-board, cardboard, or any other suitable material, preferably fibrous material or any other material which can be easily flexed. The tube 7 is somewhat longer than the tube 6, so as to provide a part 8 of reduced cross-section having an external diameter substantially equal to the internal diameter of the barrel of the lubricant compressor or other receptacle to which the lubricant from the container 5 is to be transferred. The cap 9, made preferably from the same material as the tubes 6 and 7, closes the end of the container having the projecting end portion 8 of reduced diameter, and a similar cap 10, but of slightly large diameter, closes the opposite end of the container.

I prefer to impregnate the material forming the container and the two caps with sodium silicate or any other suitable lubricant repelling material so as to prevent the lubricant from escaping through the pores of the material from which the container is formed.

Adjacent the end closure 10 of the container, and slidably within the container, I provide a plunger 11 comprising a disk portion having a central inwardly extending depression 12, and an outwardly extending peripheral flange 13. Preferably, this plunger is made of sheet iron, tin, or other similar material.

The method of filling a lubricant compressor or other lubricant receptacle with lubricant by the use of my improved lubricating means is illustrated in Figure 4. For this purpose, the cap 9 is first removed from the end of the container, and the portion 8 of reduced diameter is inserted in the end of the compressor, as shown in Figure 4. A screw driver, pencil, or any other suitable tool is then forced through the frangible closure 10, and forced downward against the plunger 11. The conical shaped central depression 12 causes the instrument thus used to seek the center of the plunger 11, and

thus prevents the plunger from tipping when continued pressure is applied to the instrument to force the plunger toward the compressor barrel for the purpose of transferring the contents of the container 5 from the container to the barrel of the compressor.

The flange 13 also tends to prevent the plunger from tipping in the container, and 10 the closure 10 prevents the dislodgment of the plunger 11 from the container during shipment.

While it is possible to make the container 5 of sheet metal, or other more or less rigid 15 material, I prefer to make it of the material specified, or other similar materials, because if, during shipment, depressions should be formed in the side walls of the container, they are easily forced outward 20 by the plunger 11 by its passage through the container so that they will not prevent the discharge of the entire contents of the container.

While I have described the details of construction of the preferred embodiment of 25 my invention, it is to be clearly understood that my invention is not to be limited to these details, but is capable of other adaptations and modifications within the scope of 30 the appended claims.

Having thus described my invention, what I claim is:

1. A package comprising a cylindrical container filled with lubricant, the said container being made of fibrous material and 35

having a removable closure at one end, a frangible closure at the other end, and a plunger slidable in said container, the said plunger having an outwardly extending flange and a central inwardly extending depression. 40

2. A package comprising a cylindrical container filled with lubricant, the said container being made of fibrous material and having a removable closure at one end, a 45 frangible closure at the other end, and a plunger slidable in said container, the said plunger having an outwardly extending flange.

3. A package comprising a cylindrical 50 container filled with lubricant, the said container being made of fibrous material and having a removable closure at one end, a frangible closure at the other end, and a plunger slidable in said container, the said 55 plunger having a central inwardly extending depression.

4. A package comprising a cylindrical container filled with lubricant, the said container being made of fibrous material and 60 having a removable closure at one end, a frangible closure at the other end, and a plunger slidable in said container.

In witness whereof, I hereunto subscribe my name this 4th day of August, 1921.

DOUGLAS F. FESLER.
